[57] CLAIM

The ornamental design for an element of a shoe upper, as shown and described.

DESCRIPTION

FIG. 1 is a side elevational view of one side of an element of a shoe upper showing our new design;

FIG. 2 is a side elevational view of the other side thereof;

FIG. 3 is a front elevational view thereof; and,

FIG. 4 is a top view thereof.

The broken line showing of a shoe sole and the remaining portion of the upper shown in FIGS. 1-4 is for illustrative purposes only and forms no part of the claimed design.
